UNITED STATES PATENT OFFICE

2,450,599

SPRAYER FOR DEHYDRATING APPARATUS

Stella A. Kloda, Chicago, Ill.

Application June 30, 1945, Serial No. 602,524

1 Claim. (Cl. 299—63)

1
The present invention relates to dehydrating apparatus and has for its main object the provision of an improved spraying head or atomizer into which liquid may be fed and from which it may be atomized or sprayed by a centrifugal force exerted thereon by the atomizer.

A still further object of the present invention is the provision of an atomizer of an improved construction having comparatively few parts which may be readily assembled or disassembled.

A still further object of the present invention is the provision of an atomizer consisting of a tray and a closure therefor with means for maintaining the two in a rigid operative position, and wherein the closure may be disengaged for providing access into the tray for removing therefrom solid matter which may accumulate therein.

With the above general objects in view and others that will appear as the invention is better understood, the same consists in the novel construction, combination and arrangement of parts hereinafter more fully described and illustrated in the accompanying drawings and pointed out in the appended claim.

In the drawing forming a part of this application, and in which like designating characters refer to corresponding parts throughout the several views:

Fig. 1 is a side elevational view of the atomizer with a motor connecting therewith for rotating the atomizer and thereby ejecting the liquid therefrom by centrifugal force;

Fig. 2 is an enlarged cross-sectional view centrally through the atomizer and on a vertical plane; and

Fig. 3 is a fragmentary, top plan view of the atomizer, partly in section, taken along line 3—3 of Fig. 2.

Referring in detail to the present drawing there is shown an atomizer having a tray including a circular bottom plate 10 and an integrally formed annular flange 11 upwardly projecting from said plate 10 and along its marginal edge. Said flange 11 is comparatively thicker than said plate 10. A plurality of closely spaced minute openings or perforations 12 are made in said flange 11 and adjacent the upper face of said plate 10, and in a radial juxta-position in relation with the latter.

Cooperating with said tray is a circular closure 13, the marginal portion of which is recessed to effect a reduced rim 14, which, in the operative position of said closure 13 upon said tray, rests upon the top end of said flange 11, and by virtue of which arrangement the body portion of

said closure 13 enters into said flange 11, as is clearly seen in Fig. 2, thereby providing a hermetical seal between said tray and said closure 13. A plurality of screws 15 passing through rim 14 and rigidly engaging flange 11, and between perforations 12, provide locking means between said tray and said closure 13.

From the hereinabove description it will be seen that said tray and said closure 13 provide a comparatively shallow chamber 16 into which liquid is fed preparatory to its ejection by the centrifugal force through said perforations 12.

Integrally formed with said plate 10, and centrally therewith, is a downwardly depending boss 17, which, at its lower end is provided with a central bore 18, into which the free end of shaft 19 is receivable. Thumb screw 20 passing through the wall of said boss 17 engages said shaft 19 and keys the same to said boss 17. Shaft 19 connects with, and is driven by an electric motor 21.

Integrally formed with said closure 13 and centrally thereof, is projection 22 upwardly extending from said closure 13. Said projection is provided with a central orifice 23, the lower portion of which is downwardly flaring for defining a conical bore 24. Receivable within said orifice 23 is pipe 25 loosely positioned in said orifice 23, and maintained in an operative position 30 with projection 22 by collar 26 resting upon the upper end of said projection 22. Connecting with said pipe 25 is conduit 27 connecting by its other end with receptacle 28 in which liquid to be dehydrated is stored. Said receptacle 28 is disposed above the atomizer so that liquid feeds thereto by virtue of gravity.

When rotary movement is imparted to the atomizer by means of shaft 19, liquid fed from receptacle 28 through conduit 27 and pipe 25 and into chamber 16 is forced, due to the centrifugal force exerted thereon by virtue of the rotation of the atomizer, to pass outwardly therefrom through apertures 12 in minute sprays or mist to be acted upon either by cold or hot air and vacuum or by various other known means for the purpose of extracting therefrom water and moisture and thus for dehydrating the same.

It is observed that pipe 25 being loosely positioned within projection 22 is stationary during the rotary movement of the atomizer. No liquid will pass through the space between the adjacent body portion of said projection 22 and said pipe 25 due to the constant suction that is exerted upon the liquid in conduit 27 and pipe 25 engendered by the centrifugal force upon the

atomizer and constant flow of the liquid therefrom through said apertures 12.

Conical bore 24 guides the liquid as it leaves pipe 25 into a funnel-like path for even radial distribution thereof into said chamber 16.

From the hereinabove description it will be readily seen that the atomizer herein disclosed may readily be disassembled by removing screws 15 for disengaging closure 13 from the tray of the atomizer for providing access into chamber 16 for thorough cleaning or washing the same or removing therefrom any solid matter accumulated therein and which was incapable of passing through apertures 12.

The atomizer herein disclosed may be used in connection with the various processes of dehydrating milk, fruit or vegetable juices.

While there is described herein a preferred embodiment of the present invention, it is nevertheless to be understood that minor changes may be made therein without departing from the spirit and scope of the invention as claimed.

What I claim as new is:

An apparatus for dehydrating liquids, comprising a tray having an annular upstanding flange with circumferentially disposed openings therethrough and integrally formed on the outer periphery of said tray, a closure for said tray seated upon said flange and cooperating with the tray to form a chamber in open communication with the openings in said flange, a shoulder on the periphery of the closure abutting the inside of said flange, means to detachably affix the closure to said flange, an upstanding projection

5 formed integral with said closure having an annular central opening therein, said opening terminating in an inverted cone in open communication with the chamber, a pipe slidably inserted into the annular central opening in the upstanding projection, a collar formed on said annular pipe adapted to rest on the upstanding projection, said pipe terminating substantially at the base of the inverted cone and being adapted to remain stationary while the cover rotates and to be removably inserted into the annular central opening of the upstanding projection, and means to rotate the tray and cover independently from the pipe and collar for discharging liquid from the tray by centrifugal force.
